US00D698833S

(12) **United States Design Patent**
Wang et al.

(10) **Patent No.:** **US D698,833 S**
(b4) **Date of Patent:** **** Feb. 4, 2014**

(54) **DEHYDRATOR**

(71) Applicant: **Hon Hai Precision Industry Co., Ltd.,**
New Taipei (TW)

(72) Inventors: **Qi Wang**, Shenzhen (CN); **Sui-Mang Song**, Shenzhen (CN); **Neng-Rong Wang**, Shenzhen (CN); **Xiao-Gang Peng**, Shenzhen (CN); **Qiong Xie**, Shenzhen (CN); **Tai-Yan Xia**, Shenzhen (CN)

(73) Assignee: **Hon Hai Precision Industry Co., Ltd.,**
New Taipei (TW)

(**) Term: **14 Years**

(21) Appl. No.: **29/459,025**

(22) Filed: **Jun. 25, 2013**

(30) **Foreign Application Priority Data**

Jun. 6, 2013 (CN) 2013 3 0235356X

(57) **CLAIM**

The ornamental design for a dehydrator, as shown and described.

DESCRIPTION

FIG. 1 is a perspective view of a dehydrator showing our design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines are for illustrative purposes only and form no part of the claimed design.
